EXTENSION BRACELET

Charles A. Domler, Providence, R. I., assignor to
The Hadley Company, Inc., Providence, R. I.,
a corporation of Rhode Island

Application May 19, 1942, Serial No. 443,591

3 Claims.

(Cl. 59—79)

This invention relates to an extensible, self-retracting bracelet and like articles of jewelry, and its principal object is to provide a bracelet linkage which is of simple design and attractive appearance, which is of light weight and of durable construction, and which embodies a minimum number of parts that can be economically manufactured and quickly assembled.

Further objects relate to various features of construction and will be apparent from a consideration of the following description and accompanying drawing, wherein:

Fig. 1 is a top plan view of a bracelet constructed in accordance with the present invention;

Fig. 2 is a side elevation of the bracelet shown in Fig. 1;

Fig. 3 is an enlarged plan view, with parts broken away, of the bracelet linkage with parts extended;

Fig. 4 is an enlarged longitudinal section through the bracelet linkage;

Fig. 5 is an enlarged transverse section through one of the pairs of links;

Fig. 6 is a view of the retracting spring; and

Fig. 7 is an enlarged detail showing the interengageable stops for limiting telescoping movement of the links from retracted to extended position.

In the embodiment herein shown for the purpose of illustration, the numerals 1 designate bracelet linkages which are pivotally interconnected at adjacent ends to a coupling link 2 and at their opposite ends to a loop-like connector or coupling 3 by means of which the ends of the bracelet may be suitably attached to a wrist watch or other article of jewelry (not shown).

Each linkage 1 comprises a plurality of pairs of links, each pair of including an outer tubular link 5 and an inner tubular link 6 telescopically disposed for sliding movement within the outer link 5, as shown in Figs. 3 to 5. The inner link of each pair is formed with a pair of spaced longitudinally extending depressions 8 (Fig. 5), and one end of each inner link is formed with a pair of outstanding lugs 10 which provide stops at the end of the depressions 8, as shown in Figs. 5 and 7. The end of each outer link, opposite the end of the inner link which carries the stops 10, is formed with inwardly projecting stops 11 engageable with the stops 10, as shown in Fig. 7, to limit telescopic movement of the links from retracted to extended position.

Each linkage 1 also includes a single coiled tension spring 12 (Fig. 6) which extends from one end of the linkage to the opposite end, as indi-

cated in Figs. 4 and 5. At points corresponding to the ends of each pair of links the convolutions of the spring 12 are distorted to provide openings 14 through which extend pivot pins 15 (Figs. 4). The pivot pins 15 project through aligned openings formed in the end of the outer link of one pair and the end of the inner link of the adjacent pair. Thus the pivot pins 15 not only pivotally connect the end of the inner link of one pair with the end of the outer link of the adjacent pair, but also serve to maintain in position the sections of the coil spring 12 defined by the distorted convolutions so that each section of the spring is operative normally to hold each pair of links in retracted position.

When a linkage constructed in accordance with the present invention is extended, the inner links of each pair slide outwardly until the stops 10 and 11 engage, as shown in Fig. 7, and when the extending force is released, each section of the spring 12 acts upon its associated inner link to effect retraction. Since the inner and outer links are substantially coextensive in length, and as the stops 10 and 11 are formed at their respective ends, the linkage herein shown may be extended to a length which is substantially twice that of its retracted position.

In the completed bracelet herein shown, two sets of linkages are employed, although it is to be understood that one or several sets of linkages may be used, and in any case but one spring for each set of links is used. In this embodiment the pivot pins 15 connect the adjacent ends of the inner links 6 to the coupling 3, and at the opposite ends of each linkage the pins merely serve to anchor the ends of the spring 12, it being noted that the outer terminal links are formed with tongues 18 by means of which the linkages are attached to the loops 3.

While I have shown and described one desirable embodiment of the invention, it is to be understood that this disclosure is for the purpose of illustration and that various changes in shape, proportion and arrangement of parts, as well as the substitution of equivalent elements for those herein shown and described, may be made without departing from the spirit and scope of the invention as set forth in the appended claims.

I claim:

1. A bracelet linkage comprising a plurality of pairs of links, each pair consisting of an outer tubular link and an inner tubular link telescopically disposed within the outer link, a coiled tension spring extending through the inner links and operative normally to maintain the links in

retracted relation, the convolutions of said spring at points corresponding to the ends of each pair of links being distorted to provide openings, and a pivot pin projecting through each opening of the distorted convolutions so as pivotally to connect the end of the inner link of one pair with the end of the outer link of the adjacent pair.

2. A bracelet linkage comprising a plurality of pairs of links, each pair consisting of an outer tubular link and an inner tubular link telescopically disposed within the outer link, one end of the outer link and the opposite end of the inner link having projecting parts providing inter-engageable stops for limiting telescopic movement from retracted to extended position, a coiled tension spring extending through the inner links and operative normally to maintain the links in retracted relation, the convolutions of said spring at points corresponding to the ends of each pair of links being distorted to provide openings, and a pivot pin projecting through each opening of the distorted convolutions so as pivotally to connect the end of the inner link of one pair with the end of the outer link of the adjacent pair.

3. A bracelet linkage comprising a plurality of pairs of links, each pair consisting of an outer tubular link and an inner tubular link telescopically disposed within the outer link, the inner link of each pair being formed with spaced longitudinally extending depressions and one end of said inner link having upstanding lugs providing stops at the end of said depressions, the outer link of each pair having inwardly projecting lugs providing stops at the end opposite the stops on the inner link, the stops being engageable to limit telescopic movement of the links from retracted to extended position, a coiled tension spring extending through the inner links and operative normally to maintain the links in retracted relation, the convolutions of said spring at points corresponding to the ends of each pair being distorted to provide openings, and a pivot pin projecting through each opening of the distorted convolutions so as pivotally to connect the end of the inner link of one pair with the end of the outer link of the adjacent pair.

CHARLES A. DOMLER.
